UNITED STATES PATENT OFFICE

2,395,522

TEXTILE APPARATUS

Pacific J. Thomas, Wyoming, Pa., assignor to
 U. S. Textile Machine Company, Scranton, Pa.,
 a corporation of Pennsylvania

Application September 2, 1944, Serial No. 552,534

20 Claims. (Cl. 242—37)

This invention relates to textile machines of the yarn winding and twisting type adapted to provide so-called "headless" yarn packages having a tapered or inclined end construction; and the novel improvements herein disclosed more particularly constitute a continuation-in-part of the subject-matter of my co-pending application Ser. No. 520,337, filed January 29, 1944.

One object of my invention is to provide a novel textile machine of the referred to type which embodies certain structural and functional features of advantage over similar machines of the prior art.

Another object is to provide such a machine having novel and improved yarn feeding means for applying the yarn to the cops, or other yarn receiving devices.

A further object is to provide such a machine in which the said yarn feeding means performs its function in novel manner and is designed to avoid play or lost motion between its movable parts.

An additional object is to provide such a machine of modern design in which the yarn feeding means is arranged to operate in a positive and efficient manner, and is also arranged to overcome certain detrimental features of the similar means of the prior art machines.

Another object is to provide such a machine in which the stroke of the yarn feeding element is controlled by the progressive variation in the diameter of the yarn receiving device or cop, and in which the mechanism provided for this purpose functions in novel manner and is adjustably arranged to achieve maximum precision of operation.

It is also an object to provide such a machine in which the yarn feeding mechanism includes a novel and simple motion translating means in the form of a cam device which can be adjusted without disturbing its connections.

Another object is to provide such a machine in which the said cam device is adapted to attain certain advantageous results in novel manner, and which can be variously controlled to effect the performance of its intended function.

A still further object is to provide a yarn feeding mechanism of the indicated type, which can be readily applied to a modern yarn winding and twisting machine as an attachment, to thereby increase the operating and output efficiency of the machine and impart to the machine the above referred to and other advantages.

With these and other objects in view, which will become more apparent from the following

detailed description of the practical and illustrative embodiments of my novel improvements shown in the accompanying drawings, the invention comprises the novel elements, features of construction and arrangement of parts in cooperative relationship, as more particularly defined by the hereto appended claims.

Referring to the drawings:

Fig. 11 is an enlarged detail sectional view taken substantially as indicated by the arrows 11—11 on Fig. 2.

Fig. 12 is a partial front elevational view of the apparatus shown in the previous illustrations, having a modified form of my invention applied thereto.

Fig. 13 is a plan view of Fig. 12, certain parts being broken away and others omitted.

Fig. 14 is a view similar to Fig. 6, but of the modified form of my invention.

Fig. 15 is a fragmentary elevational sectional view, on an enlarged scale, taken substantially as indicated by the arrows 15—15 on Fig. 12.

In the drawings only those parts of a standard or conventional yarn winding and twisting machine of the "up-twister" type are shown as are

necessary to a disclosure and understanding of my invention. For further information concerning the construction and operation of such machines, reference may be had to the various pertinent catalogs and other literature published for distribution by the U. S. Textile Machine Co. of Scranton, Pennsylvania, and other manufacturers of such machines. For complete information concerning certain prior art elements and mechanisms only partly illustrated in the drawings hereof, reference may also be had to the following U. S. Patents:

Number	Date	Inventor
2,258,914	Oct. 14, 1941	P. J. Thomas.
2,258,899	Oct. 14, 1941	Royal Little et al.
2,258,900	Oct. 14, 1941	Royal Little et al.

In the embodiment of my invention shown in Figs. 1 to 11 inclusive, the usual and well-known parts of each individual unit of the yarn winding and twisting machine include a yarn supply spool 20, mounted on and rotated with a twister spindle 21, and a take-up roll, cop or device 22 which is operated by direct frictional engagement with a driving drum 23. In accordance with standard practice, the twister spindle 21 and driving drum 23 are continuously rotated in proper direction at predetermined twisting and winding speeds. The yarn Y is drawn upwardly from the spool 20, through yarn guides 24 and 25, through a yarn breakage detector element 26, over a fixed guide member 27, through a yarn guide or feeding element 28, to the surface of the take-up roll 22. The yarn guide member 27 is provided at its ends with enlargements or collars 27^a having hooks 27^b. The yarn feeding element 28 is reciprocated by a traversing rod 29 extending lengthwise of the machine and guided for movement in a multiplicity of roller bearings 31, as determined by the usual traversing rod operating mechanism, not shown. Determined reciprocation of the yarn guide element 28 by stroke control means hereinafter described, effects the laying of the yarn Y on the take-up roll 22 in desired order.

The take-up roll 22 is provided, as usual, with trunnions 22^a which are adapted to be seated for rotary movement in slotted bearing elements 32^c clamped in adjusted position by bolts 32^b between the split sections of the bifurcated upper ends 32^a of a swinging support or frame 32. Secured in the lower side sections of the frame 32 are two pivot studs 33 which turnably extend into fixed bearings 34 of a bracket 35 rigidly connected with a stationary machine frame member 36. A spiral compression spring 37 is interposed between a cup-shaped extension or projecting member 38 on the bearing bracket 35, and a similar but inverted cup-shaped extension 39 projecting rearwardly from the lower end of frame 32. This arrangement causes the spring 37 to urge the supporting frame 32 and device 22 to move forwardly, or in a direction away from the driving drum 23. However, this tendency of movement of the frame 32 is normally counteracted and overcome by the force of a relatively stronger spiral tension spring 41, one end of which is anchored to an extension 42^a at the rear end of a flat slide bar 42, and the other end of which spring is connected to a stud 43 extending through an elongated slot 42^b in the bar 42 and fixed in a side section of the frame 32. The spring 41 is tensionally arranged between the stud 43 and extension 42^a in such manner as to normally maintain the take-up

roll 22 in yielding operating contact with the driving drum 23.

The bar 42, yarn guide 25, yarn breakage detector element 26, and certain associated devices partly shown in Figs. 1, 4, 6 and 8, are arranged to form a stop motion mechanism corresponding with the stop motion mechanism fully disclosed in my above noted Patent No. 2,258,914, to which reference may be had for a complete exposition of the construction, arrangement and operation thereof. When the yarn Y breaks, or runs out, 10 the yarn detector element 26 of this mechanism is permitted to move so as to effect release of the bar 42 for movement forwardly, or to the left in Figs. 6 and 8, thereby to eliminate the action of spring 41 on frame 32 as previously explained, and, under the influence of compression spring 37, the frame 32 is then forced to swing forwardly to an extent breaking the driving contact between 15 the roll 22 and the drum 23. Rotation of the take-up device 22 thereupon promptly ceases. The forward end of the bar 42 is provided with a finger knob 55 for convenient resetting of the bar 42 and spring 41, so that the stop motion mechanism may function as before.

Cooperatively combined with the previously described elements and mechanisms are novel means for controlling the stroke of the yarn feed element 28 to effect winding of successive layers of 30 yarn Y on the take-up cop or cylinder 22 in such manner that the yarn and cop will form a so-called "headless" yarn package having tapered ends of desired angular inclination, substantially as shown in Fig. 9. Such means generally comprise a track member 44, a carriage 45, a plunger 46 the upper end of which is pivotally connected with the track member 44 by a pin 47, and the lower extremity or tip of which cooperatively rests on the upper flat surface of an inverted 35 U-shaped arm 48 pivotally connected at 49 to the swinging frame 32. The plunger 46 is freely 40 slideable vertically in a bearing or guide 51, formed in or otherwise associated with a stationary machine beam 52.

An intermediate vertically extending reinforced 45 section 44^a of the track member 44 is pivotally mounted to afford tilting action of the latter, in the upper bifurcated end of a shouldered bolt 53, by a stud screw 54, and the bolt 53 is fixedly secured to the stationary machine beam 52, as clearly shown in Fig. 10. A horizontally extending 50 flange 44^b of the track member 44 serves as a runway for a roller 56 secured for free rotation to the carriage 45, and the latter is pivotally connected by a shouldered stud rivet 57 with a bracket 58 fixed to the traversing bar 29, as clearly 55 shown in Fig. 3.

In order that the roller 56 may be constantly maintained in cooperative relation with the runway flange 44^b of the track member 44, a spring wire 59 is coiled about the shouldered stud rivet 57, one end of which wire rests on an extension 60 of the bracket 58, and the other end of which wire rests on the upper edge of the carriage 45, as 60 more particularly shown in Fig. 5. By this arrangement the spring wire 59 exerts a downward pressure on the portion of the carriage 45 to the left (Fig. 5) of its pivotal connection with the bracket 58, thereby maintaining the roller 56 in constant engagement with the runway flange 44^b.

The yarn guide or feed element 28 is secured to the upper section of a plate 61, and the lower end of the latter is pivotally connected with the 65 carriage 45 by means of a horizontally extending

pin 62 the ends of which are turnably supported in bearing flanges 63 of the carriage. This arrangement permits the element 28 to be freely moved or swung laterally with respect to the take-up roll or device 22, so that when placed in active position, to the right of pin 62 (Figs. 6 and 8) the element 28 will lean against the yarn receiving surface of the bobbin, and will be maintained in such position by the force of gravity acting on the element 28 and its mounting plate 61. The upper feeding end of the element 28 is rounded and arranged to directly rest against the take-up roll 22, or the yarn receiving surface thereof established by the successive yarn layers as the winding of the yarn proceeds. Since the element 28 will at all times be positioned to the right of the pivot pin 62, during a particular yarn winding operation or cycle (Figs. 6 and 8), contact of the element 28 with the yarn receiving surface of the take-up roll 22 will be constantly and automatically maintained during such cycle by the action of gravitational force exerted on the parts as previously explained. Of course, if desired, a spring may be connected to the plate 61 and carriage 45 in such manner that the spring will either supplement, or serve the same purpose as the gravitational force.

The left end of the track member 44 (Fig. 2) is arranged to be urged or biased upwardly by means of a spring actuated plunger device shown more particularly in Fig. 11. This device comprises a socket 65 secured to a plate or bracket 65^a which is fixedly connected to the frame 52, a spiral compression spring 66, and a plunger 67 the upper end or head of which is provided with a suitable slot in which slidably rests a portion of the reinforced or enlarged vertically extending edge section 44^a of the track member 44. The said spring actuated device functions to yieldingly force the tip of the cam plunger 46, located at the other end of the track member 44, against the upper surface of the front end of arm 48.

A cam element 68, of similar inverted U-shaped cross-sectional configuration as the arm 48, is adjustably mounted in the lower front section of the arm 48. The rear end of the element 68 is pivotally secured to the arm 48 by a screw stud 69, and the bottom edges of the side members or legs of the element 68, at their front end, form two correspondingly inclined cam edges 68^a which are adapted to rest on and cooperate with a roller 70 rotatably secured in the U-shaped section of a bracket 71 fixed to the stationary machine frame member 52. A cam adjustment screw 72 extends through, and has threaded engagement with, an aperture 73 in the upper front wall section of the arm 48, and the lower end or tip of said screw is in contact with the upper front wall section of the cam element 68. A lock nut 74 is provided on the screw 72 and is arranged to secure the screw in adjusted position.

Since the arm 48 moves in unison with the swingable frame 32 on which the device 22 is mounted, the cam element 68 is moved in correspondence with the forward motion imparted to the frame 32 by the progressive increase in the diameter of the cop 22 when one yarn layer after another is applied to it by the yarn feed element 28. The similar cam edges 68^a of the cam element 68 are so designed and arranged that the gradual forward movement imparted to the latter in the indicated manner, will effect a correspondingly progressive lowering of the plunger 46, as the edges 68^a move over the roller 70, with

the result that the track member 44 is tilted by an incremental amount sufficient to properly vary the stroke of the yarn feeding element 28 as required in order that the yarn package ends be given the desired degree of taper or angular inclination. The said action attained by the arrangement described is so precise, that the development of so-called "cross-overs" of the yarn at the package ends cannot occur under normal circumstances.

Since standard or conventional yarn winding and twisting machines of the type herein referred to usually comprise a long frame structure along both sides of which are arranged duplicate rows of similar machine units, it will be understood that the machine or apparatus of my invention is similarly provided with the usual complement of corresponding units of the type previously described. Also, that these units are collectively operated in accordance with prior art practice by the usual means and in the usual manner well known to those skilled in this art.

Operation

When starting a yarn package, the end of the yarn Y is wrapped around a fresh or empty take-up roll or cylinder 22, in usual manner, and the latter is then mounted in its bearing elements 32^c at the upper end of the swinging frame 32. The bar 42 is then moved rearwardly by manual pressure on the knob 55 until the spring 41 is under the tension required to place the take-up roll 22 in driving contact with the drum 23, and the previously referred to "stop motion mechanism" is set for operation in accordance with the disclosure of my said Patent No. 2,258,914. The various elements and mechanisms will then be cooperatively related substantially as shown in Fig. 6.

Rotation of the yarn supply spool 20 and driving drum 23, as usual, effects procedure of the yarn winding and twisting operation. As the successive yarn layers on the take-up roll 22 move the upper end of the swinging frame 32 laterally away from the drum 23, the arm 48 and cam element 68 will be simultaneously moved forward, with the result that the plunger 46 will be gradually and progressively lowered in correspondence with the upper surface of the front end of arm 48, as determined by the action of cam edges 68^a traveling on the freely rotatable but stationarily mounted roller 70. This motion of the plunger 46 is directly transmitted to the track member 44 through the pin connection 55 47, and the track member 44 is consequently tilted from its initial horizontal position by an amount as determined by the design of the cam edges 68^a, and the movement imparted to cam element 68 by the take-up device support 32 as the diameter of the take-up roll 22 increases.

Reciprocation of the carriage 45 by the traversing rod or bar 29 effects movement of the roller 56 along the runway 44^b of track member 44, back and forth, thereby correspondingly moving the yarn feed element 28 at the upper end of the plate 61 which is pivotally connected with the carriage 45. As the angle of tilt of the track member 44 increases, the stroke of the yarn feed element 28 is shortened, or decreases by an incremental amount at each end. This will become more apparent by reference to Fig. 9, which depicts the carriage 45 and the yarn feed element 28 at the extreme ends of their stroke to the right and left, at the time that the take-up roll 22 is substantially supplied with its in-

tended quantity of yarn. At this time, the swinging frame 32, arm 48, cam element 68, plunger 46 and the cooperatively associated parts, will occupy positions substantially as depicted in Fig. 8.

Should the yarn Y break, or run out, during the yarn winding and twisting operation, or cycle, the detector element 26 will release the bar 42 for movement to the left (Figs. 6 and 8), as previously explained, thereby effecting immediate disengagement of the take-up roll 22 and driving drum 23, so that rotation of the roll 22 ceases.

It is to be noted that during the winding operation, the yarn feed element 28 is continuously in direct leaning contact with the surface to which the yarn is applied, and that the yarn is consequently guided to its exact point of application at all times during the active functioning of the machine. This feature, in conjunction with the means for progressively varying the stroke of the yarn feed element in direct correspondence with the total thickness, or diameter, of the yarn layers applied to the take-up roll 22, results in the same precise yarn applying action under varying conditions, such as a change in operating speed of the machine, or change in the denier of the yarn wound on the device 22.

It is also to be particularly noted that the arm 48, cam element 68, roller 10, adjustment screw 12, plunger 46, and the parts cooperatively associated therewith, collectively provide a simple, efficient and effective means or arrangement for precisely and automatically controlling the stroke of the yarn feed element 28 in direct correspondence with the progressive change or increase in diameter of the yarn take-up device 22. Furthermore, that play or lost motion resulting in time from wear between certain of these parts can be quickly and easily compensated for by the adjustment screw 12, which is readily accessible for adjustment from the front of the machine. In other words, the screw 12 facilitates the establishment and maintenance of an exact relationship between the angular position of the track member 44 and the cam edges 68^a, without necessitating the disturbance of any connections of the cooperating parts of the cam device.

Modifications

In accordance with the second form of my invention disclosed in Figs. 12, 13, 14 and 15 of the drawings, a modified form of cam means or device is substituted for that disclosed in Figs. 1 to 11 inclusive. Since the apparatus is otherwise the same, the previously described parts will be designated by the same reference characters to avoid repetition of their description.

As clearly shown, the said substitute cam device comprises an arm 75, which takes the place of the arm 48 of the previously described mechanism, and has associated therewith a longitudinally slidable cam element 76. The arm 75 is pivotally secured to the swingable frame 32 by a pin 77, and has a slot 78 in its upper wall. In shape and size, the arm 75 corresponds substantially with the arm 48.

The cam element 76 is substantially the same in configuration as the cam element 68, and comprises cam edges 76^a which correspond substantially with the cam edges 68^a of the cam 68, a slot or aperture 79, and an abutment or cam slide stop extension 81, adapted to cooperate

with the pin or stud 77 on which the arm 75 is pivotally mounted. The cam slide 76 is cooperatively associated with the arm 75 in telescopic manner for free reciprocating movement in a longitudinal direction within the confines of the side and top walls of the arm 75, as clearly shown in Figs. 12 and 15.

10 The abutment extension 81 serves to prevent unintentional disconnection or dislodgment of the cam slide from the arm 75, when it carries out its forward movement, and is arranged to stop such movement of the slide 76 when the extension 81 abuts the pin 77.

15 The cam slide 76 is actuated by a curved extension 82^a of a substantially rectangular frame 82, which latter is pivotally connected between the bifurcations 32^a of the swinging frame 32 by two screw studs 83. The upper end of the frame 82 has transversely mounted between the side members thereof a freely rotatable roller 84 in turn contactingly arranged intermediate the driving drum 23 and the take-up roll 22. This arrangement of the roller 84 results in 20 transmission of the rotary movement of the driving drum 23 to the take-up device 22.

25 A spring wire 85 is coiled about a side extension of frame 82, adjacent one of the screw studs 83, as clearly shown in Figs. 12 and 14, one end of which wire is hooked about the frame 82 and the other anchored on the adjacent leg 32^a of the swingable frame 32. This arrangement of the spring wire 85 urges the frame 82 to swing forwardly (to the left in Fig. 14) so as to constantly maintain the roller 84 in yielding contact with 30 the take-up bobbin 22.

35 The lower end of the curved extension 82^a passes through the elongated slot 78 in arm 75, and through the aperture 79 in the cam slide 68. The aperture 79 is of such shape and size as 40 to permit the extension 82^a to freely move therethrough vertically, during its changing angular position, and in such manner that the front and rear edge surfaces of the extension 82^a may operate with the front and rear wall surfaces of 45 the aperture 79, so as to establish a close fitting sliding connection between the extension 82^a and the cam element 76. The extension 82^a, during the time that the swinging frame 32 moves or tilts forwardly, has a composite movement consisting 50 of the same forward movement as the frame 32, at the point of location of the screw studs 83, and a slight vertical movement, as determined by the gradual change in location of the roller 84 relative to the center of take-up device 22, when the latter increases in diameter due to the winding of 55 yarn thereon. This composite movement is taken into account in connection with the design and arrangement of the cam edges 76^a, so that the movement imparted to the plunger 46 is the same 60 as that imparted thereto by the cam means of Figs. 1 to 11 inclusive.

65 From the foregoing description it will be apparent that the cam device or arrangement disclosed in Figs. 12 to 15 inclusive, accomplishes the same result as the cam means or arrangement of Figs. 1 to 11 inclusive. Consequently, that either of the two disclosed cam devices may be utilized, as desired and considered best in connection with the embodiment of my invention in textile machines 70 as herein exemplified.

75 Of course, other changes and modifications than those specifically shown and described can be made without departing from the invention herein disclosed and more particularly defined by the hereto appended claims.

I claim:

1. A textile apparatus of the character described comprising, a movable mounting, a yarn receiving device rotatably supported on said mounting, a yarn feeding element arranged to contactingly move along the yarn receiving surface of said device, tilttable track means, carriage means arranged to travel on said track means, means connecting said element with the carriage means, and a cam device arranged to determine the angle of tilt of said track means. 5
2. A textile apparatus of the character described comprising, a movable mounting, a yarn receiving device rotatably supported on said mounting, a yarn feeding element arranged to lean against and move along the yarn receiving surface of said device, tilttable track means, carriage means arranged to travel on said track means, means connecting said element with the carriage means, and an adjustable cam device arranged to determine the angle of tilt of said track means. 10
3. A textile apparatus of the character described comprising, a movable mounting, a yarn receiving device rotatably supported on said mounting, a yarn feeding element arranged to lean against and move along the yarn receiving surface of said device, tilttable track means, carriage means arranged to travel on said track means, means connecting said element with the carriage means, and a cam device connecting said movable mounting and the track means which device is arranged to determine the angle of tilt of said track means. 15
4. A textile apparatus of the character described comprising, a movable mounting, a yarn receiving device rotatably mounted on said mounting, a yarn feeding element arranged to lean against and move along the yarn receiving surface of said device, tilttable track means, carriage means arranged to travel on said track means, means connecting said element with the carriage means, and an adjustable cam device connecting said movable mounting and track means in such manner that adjustment thereof can be effected without disturbing its connections. 20
5. A textile apparatus of the character described comprising, a movable mounting, a yarn receiving device rotatably supported on said mounting, a yarn feeding element arranged to lean against and move along the yarn receiving surface of said device, tilttable track means, carriage means arranged to travel on said track means, means connecting said element with the carriage means, a cam device connected with said movable mounting, and motion translating means cooperatively connecting said track means and cam device and arranged to tilt the track means as determined by the action of the cam device. 25
6. A textile apparatus of the character described comprising, a movable mounting, a yarn receiving device rotatably supported on said mounting, a yarn feeding element arranged to contactingly move along the yarn receiving surface of said device, tilttable track means, carriage means arranged to travel on said track means, means connecting said element with the carriage means, a cam device connected with said movable mounting and operative transversely relative to the track means, and motion translating means cooperatively connecting said track means and device and arranged to tilt the track means as determined by the action of the cam device. 30
7. A textile apparatus of the character described comprising, a movable mounting, a yarn receiving member rotatably supported on said mounting, a yarn feeding element arranged to contactingly move along the yarn receiving surface of said member, tilttable track means, carriage means arranged to travel on said track means, means pivotally connecting said element with the carriage means, a device having one end portion thereof connected with said movable mounting and provided with cam means at its other end, and means cooperatively connecting said track means and device so as to effect tilting of the track means as determined by the action of the device. 35
8. A textile apparatus of the character described comprising, a movable mounting, a yarn receiving member rotatably supported on said mounting, a yarn feeding element arranged to contactingly move along the yarn receiving surface of said member, tilttable track means, carriage means arranged to travel on said track means, means connecting said element with the carriage means, a device having one end portion thereof pivotally connected with said movable mounting and provided with adjustable cam means at its other end, and motion translating means cooperatively connecting said track means and device and arranged to tilt the track means as determined by the action of the device. 40
9. A textile apparatus of the character described comprising, a movable mounting, a yarn receiving member rotatably supported on said mounting, a yarn feeding element arranged to contactingly move along the yarn receiving surface of said member, tilttable track means, carriage means arranged to travel on said track means, means connecting said element with the carriage means, a device having one end portion thereof pivotally connected with said movable mounting and provided with adjustable cam means at its other end arranged to move transversely of the track means, and means cooperatively connecting said track means and device so as to effect tilting of the track means as determined by the action of the device. 45
10. A textile apparatus of the character described comprising, a movable mounting, a yarn receiving device rotatably supported on said mounting, a yarn feeding element arranged to contactingly move along the yarn receiving surface of said device, tilttable track means, carriage means arranged to travel on said track means, means connecting said element with the carriage means, a stationary frame member on which the track means is pivotally supported, spring actuated means supported on said frame and arranged to bias the track means in one direction, a cam device pivotally connected with said movable mounting and arranged to have transverse sliding engagement with the frame member, and means cooperatively connecting said track means and cam device and arranged to tilt the track means as determined by the action of the cam device. 50
11. A textile apparatus of the character described comprising, a movable mounting, a yarn receiving device rotatably supported on said mounting, a yarn feeding element arranged to contactingly move along the yarn receiving surface of said device, tilttable track means, carriage means arranged to travel on said track means, means connecting said element with the carriage means, a stationary frame member on which the track means is pivotally supported, spring actuated means supported on said frame member and arranged to bias the track means in one direction, 55
- 70
- 75

a roller associated with said frame, a cam device pivotally connected with said mounting and having a straight portion and a cam section arranged in transverse sliding engagement with said roller, means cooperatively connecting said track means and said straight portion of the cam device so as to effect tilting of the track means as determined by the action of the cam device, and adjustable means adapted to vary the distance between said straight portion and the cam section.

12. A textile apparatus of the character described comprising, a source of yarn supply, a movable mounting, a yarn receiving device rotatably supported on said mounting, a driving drum in contacting connection with the yarn receiving device, a yarn feeding element arranged to contactingly move along the yarn receiving surface of said device, tilttable track means, carriage means arranged to travel on said track means, means connecting said element with the carriage means, a cam device arranged to determine the angle of tilt of said track means, and means arranged to effect disconnection of the yarn receiving device from the driving drum upon interruption of the yarn moving from the yarn supply to said yarn feeding element.

13. A textile apparatus of the character described comprising, a movable mounting, a yarn receiving device rotatably supported on said mounting, a driving drum, a yarn feeding element, longitudinally tilttable track means, carriage means arranged to travel on said track means, means connecting said element with the carriage means, a cam device arranged to determine the angle of tilt of the track means, rotary means cooperatively associated with the yarn receiving device and driving drum, and movable means cooperatively connecting said rotary means, movable mounting and cam device so as to effect movement of the cam device in correspondence with variation in the diameter of the yarn receiving device.

14. A textile apparatus of the character described comprising, a movable mounting, a yarn receiving device rotatably supported on said mounting, a driving drum, a yarn feeding element, longitudinally tilttable track means, carriage means arranged to travel on said track means, means connecting said element with the carriage means, an adjustable cam device arranged to determine the angle of tilt of the track means, rotary means cooperatively positioned intermediate the yarn receiving device and driving drum, and a lever cooperatively connecting said rotary means, movable mounting and cam device so that the lever will effect movement of the cam device in correspondence with variation in the diameter of the yarn receiving device.

15. A textile apparatus of the character described comprising, a movable mounting, a yarn receiving device rotatably supported on said mounting, a driving drum, a yarn feeding element, longitudinally tilttable track means, carriage means arranged to travel on said track means, means connecting said element with the carriage means, a cam device arranged to determine the angle of tilt of the track means, a freely rotatable roller arranged in contacting relationship intermediate the yarn receiving device and driving drum, and means pivotally supported on said movable mounting which means is cooperatively connected with said cam device and said roller so as to effect movement of the cam device in correspondence with variation in the diameter of the yarn receiving device.

16. A textile apparatus of the character described comprising, a movable mounting, a yarn receiving device rotatably supported on said mounting, a driving drum, a yarn feeding element, longitudinally tilttable track means, carriage means arranged to travel on said track means, means connecting said element with the carriage means, a cam device arranged to determine the angle of tilt of the track means, a freely rotatable roller arranged in contacting relationship intermediate the yarn receiving device and driving drum, and a frame pivotally supported on said movable mounting which frame is arranged to carry said roller and has an extension in sliding engagement with said cam device so as to effect movement of the cam device in correspondence with variation in the diameter of the yarn receiving device.

17. A textile apparatus of the character described comprising, a movable mounting, a yarn receiving device rotatably supported on said mounting, a driving drum, a yarn feeding element, longitudinally tilttable track means, carriage means arranged to travel on said track means, means connecting said element with the carriage means, a cam device arranged to determine the angle of tilt of the track means, a freely rotatable roller arranged in contacting relationship intermediate the yarn receiving device and driving drum, and lever means pivotally supported on said movable mounting one end of which is provided with a cam surface in sliding engagement with said cam device and the other end of which is adapted to support said roller.

18. A textile apparatus of the character described comprising, a movable mounting, a yarn receiving device rotatably supported on said mounting, a driving drum, a yarn feeding element, longitudinally tilttable track means, carriage means arranged to travel on said track means, means connecting said element with the carriage means, an adjustable cam device one end of which is pivotally connected with said movable mounting and the other end of which is arranged to move transversely relative to said track means, means cooperatively connecting said cam device and track means, a freely rotatable roller arranged in contacting relationship intermediate the yarn receiving device and driving drum, and lever means pivotally supported on said movable mounting one end of which is provided with a cam surface arranged to cooperate with a slotted portion of said cam device and the other end of which is adapted to support said roller.

19. A textile apparatus of the character described comprising, a source of yarn supply, a movable mounting, a yarn receiving device rotatably supported on said mounting, a driving drum, a yarn feeding element arranged to contactingly move along the yarn receiving surface of said device, tilttable track means, carriage means arranged to travel on said track means, means connecting said element with the carriage means, a cam device arranged to determine the angle of tilt of said track means, rotary means contactingly associated with the yarn receiving device and driving drum, movable means cooperatively connecting said rotary means, movable mounting and cam device so as to effect movement of the cam device in correspondence with variation in the diameter of the yarn receiving device, and means arranged to effect disconnection of the yarn receiving device from the rotary means upon interruption of the yarn moving from the yarn supply to said yarn feeding element.

20. A textile apparatus of the character described comprising, a source of yarn supply, a movable mounting, a yarn receiving device rotatably supported on said mounting, a driving drum, a yarn feeding element arranged to lean against and move along the yarn receiving surface of said device, tilttable track means, carriage means arranged to travel back and forth on said track means, means pivotally connecting said element with the carriage means, a cam device arranged to determine the angle of tilt of said track

5 means, a freely rotatable roller contactingly positioned between the yarn receiving device and driving drum, lever means pivotally supported on said movable mounting one end of which is arranged to cooperate with said cam device and the other end of which is adapted to support said roller, and means arranged to effect disconnection of the yarn receiving device from the roller upon interruption of the yarn moving from the yarn supply 10 to said yarn feeding element.
